PLEASURE BOAT DECK

Robert H. Madding, 914 Wallace Bldg., Little Rock, Ark.

Filed Feb. 1, 1960, Ser. No. 59,228

Term of patent 3½ years

(Cl. D71—1)

Fig. 1 is a top plan view of a boat deck embodying my new design;

Fig. 2 is a side elevation of Fig. 1;

Fig. 3 is a bow view of Fig. 1;

Fig. 4 is a stern view of Fig. 1;

Fig. 5 is a section on line 5—5 of Fig. 1;

Fig. 6 is a fragmentary perspective view of the bow portion of the deck shown in Fig. 1.

The hull shown in broken lines is included for illustrative purposes only.

I claim:

The ornamental design for a pleasure boat deck, substantially as shown and described.
